UNITED STATES PATENT OFFICE

93,341

DESIGN FOR A COMBINATION BOTTLE AND BASE

Paul H. Ganz, New York, N. Y., assignor to D. Lisner & Co., New York, N. Y., a corporation of New York

Application February 1, 1934, Serial No. 50,585

Term of patent 14 years

To all whom it may concern:

Be it known that I, PAUL H. GANZ, a citizen of the United States, residing in the city, county and State of New York, have invented a new, original and ornamental Design for a Combination Bottle and Base, of which the following is a specification, reference being had to the accompanying drawing, forming part thereof.

I claim as my invention:

The ornamental design for a combination bottle and base as shown.

PAUL H. GANZ.
